NONCLOGGING ATOMIZER

Paul P. Frauchione, Lakewood, Ohio

Application June 26, 1947, Serial No. 757,265

6 Claims. (Cl. 299—88)

1

This invention relates to an atomizer and, while not limited thereto, is particularly adapted for use with hair dressing compositions of the type commonly designated "lacquers."

In the hair dressing art it is frequently desirable to apply a quick drying preparation of the type commonly referred to as a "lacquer" to the hair of a patron for the purpose of retaining the latter in a desired coiffure. Various methods have been employed for applying such solutions of which spraying the solution upon the hair is perhaps the easiest and quickest mode of application. Nevertheless, attempts to use conventional atomizers for this purpose result in considerable difficulties and delays because the solutions employed are quick drying and somewhat adhesive with the result that the conventional atomizers very quickly become clogged and inoperative. Since the conventional atomizers employ a construction which is difficult to clean, their use for this purpose is far from satisfactory.

It is, therefore, an object of this invention to provide a novel and improved atomizer which is so constructed and arranged that it does not easily become clogged even when employed with relatively adhesive and/or quick drying solutions.

Another object of the invention is to provide an improved atomizer for use with hair lacquer or the like and which may be more readily cleaned if it becomes clogged by drying of the solution thereon.

A further object of the invention is to provide a novel and improved atomizer in which the upper end of the tube or nozzle through which the solution is drawn is normally spaced a relatively large distance from the tube through which a blast of air issues for producing the spray, and in which the latter tube is provided with a portion which is automatically advanced relatively close to the upper end of the liquid conveying tube during operation of the atomizer and is retracted when the latter is not in operation.

An additional object of the invention is to provide a novel and improved atomizer which is of rugged construction, is pleasing in appearance, inexpensive to manufacture, and which may be readily employed with quick drying and/or adhesive fluids to produce a fine spray thereof with less clogging than in prior constructions.

The invention further resides in certain novel features of construction, and combinations and arrangements of parts, and further objects and

2

advantages thereof will be apparent to those skilled in the art to which it pertains from the following description of the present preferred embodiment thereof, described with reference to the accompanying drawing in which similar reference characters represent corresponding parts throughout the several views, and in which:

Fig. 1 is an enlarged view, partially in side elevation and partially in section, of an atomizer constructed in accordance with this invention, the portion in section being taken substantially along the line 1—1 of Fig. 3 and looking in the direction indicated by the arrows;

Fig. 2 is a fragmentary view, partially in side elevation and partially in section, illustrating the atomizer shown in Fig. 1 in operation; and

Fig. 3 is a fragmentary plan view of the bulb and cap member of the atomizer illustrated in Figs. 1 and 2.

The embodiment of the atomizer illustrated in the drawings comprises a container or flask 10 for the liquid to be sprayed or vaporized. This container may have any desired shape but is here illustrated as being of frusto-conical configuration and having an upstanding screw-threaded neck portion 11 upon which is screwed a cap member 12. The cap member 12 may be formed of plastic, hard rubber, metal or any similar material and is provided with an integral upstanding bracket or flange portion 13 disposed at one side of a central opening 14 through the top of the cap member. Within the opening 14 of the cap 12 is removably positioned the lower end of a plug member 15, the upper portion of which extends above the top of the cap 12 and may have any desired configuration. Extending centrally through the plug member 15 is a hollow bore within which is positioned a nozzle member 16 having a relatively small diameter bore therethrough, the member 16 being provided with a shoulder which engages the upper end of the plug 15. The lower end of the nozzle member 16 communicates the upper end of a counterbore in the lower end of the plug 15 and within this counterbore is positioned the upper end of a vertical extending tube 17, the lower end of which extends closely adjacent the bottom of the flask or container 10. It will be observed that the diameter of the tube 17 is considerably greater than that of the bore in the nozzle member 16, thereby facilitating the return of the solution within the nozzle member, after use of the atomizer is terminated, as will be hereinafter described.

In the construction shown, the cap 12 is formed

of plastic, as is also the plug 15, while the nozzle member 16 is formed of metal such as brass and the tube 17 is formed of glass. As so constructed, the upper end of the tube 17 is frictionally held within the counterbore of the plug member 15 so as to be readily removable therefrom while the lower portion of the plug member 15 is likewise frictionally and sealingly held within the opening 14 in the top of the cap member. While the parts have been illustrated and described as formed of separate members and of different materials, it will be apparent that the plug member, nozzle and tube 17 may all be formed integrally of the same material, if desired. It is also possible to form the cap 12 integral with these parts by casting or molding them of plastic or the like. However, the illustrated construction is preferred because of the ease of manufacture and because it enables the parts to be more readily cleaned when necessary.

The cap member 12 is additionally provided with an opening 18, of relatively small diameter, within which a rod 19 of wire or the like is loosely and slidably disposed, the upper end of this wire being bent as illustrated in Fig. 3 to prevent the rod from dropping into the container or flask 10. This rod may be readily removed and employed for cleaning the atomizer as will hereinafter appear and, since the rod has a relatively loose fit within the bore 18, a small entrance for air is provided to replace the liquid which is removed from the container 10 by operation of the atomizer as hereinafter described.

The flange or bracket 13 has an outwardly extending, substantially cylindrical portion 20 through which extends a bore 21, the outer end of which is counterbored to receive the flange of a bushing 22. The shank of the bushing 22 extends within the bore 21 and a tube 23 is slidable within the bushing 22 and the bore 21. The inner end of the tube 23 is provided with a flanged portion 24 disposed within the bore 21 and slidable therein. The tube 23 is retained within the bushing 22 and the bore 21 by means of a short sleeve or bushing 25 which is fitted in the opposite end of the bore 21 from that in which the bushing 22 is disposed, the inner end of the sleeve or bushing 25 being spaced from the inner end of the bushing 22. The outer surface of the cylindrical portion 20 of the bracket or flange 13 is provided with a circular groove within which is fitted the inturned flange portion 26, surrounding the air exhaust opening, of a resilient syringe bulb 27 of conventional construction.

It will be observed that the cylindrical portion 20 and the bore 21 therethrough are inclined so that, when the atomizer is not in use, the tube 23 is positioned substantially as shown in Fig. 1 with its flanged portion 24 abutting against the inner end of the sleeve or bushing 25. The tube 23 will assume this position due to the incline of the bore 21 and also due to the action of the air which is drawn into the bulb 27 when the latter is released after having been compressed. When the bulb 27 has but one opening therein, as shown, it is not necessary that the bore 21 be inclined since the air entering the bulb, when the latter expands after being compressed, will retract the movable tube 23. However, the bulb 27 may be of the type in which a valved air inlet opening is provided in addition to the exhaust opening in communication with the bore 21.

When the latter type of bulb is employed, the bore 21 must either be inclined, as shown in Fig. 1 or 2, or a light compression spring provided between the flange 24 and the inner end of the bushing 22 to retract the tube 23 when the bulb is allowed to expand after having been compressed.

When the parts are in the position shown in Fig. 1, the outer end of the tube 23 is spaced a relatively large distance from the upper end of the nozzle 16. Hence any of the hair lacquer or other solution which may have collected about the top of the nozzle 16 cannot come in contact with the end of the tube 23 and dry over the opening therein. Also, the retraction of the tube 23, each time the bulb expands, insures that any mist or spray resulting from operation of the atomizer will not be drawn into the bulb 27 since the outer end of the tube 23 is withdrawn from the vicinity of the top of nozzle 16 as soon as the bulb begins to draw air therein.

With an atomizer constructed in the manner shown in the drawing, the cap 12 is removed from the container 10, the liquid to be sprayed is placed within the container, and the cap 12 is then screwed upon the top of the container. If a sufficiently tight seal is not secured between the cap 12 and the top of the neck 11 a gasket 28 may be employed therebetween in the conventional manner. In using the atomizer the operator grasps the flask 10 in one hand and the bulb 27 in the other. Upon squeezing or compressing the bulb 27 the air contained therein is forced outwardly through the bore 21 in the flange member 13. A part of this air in passing outwardly, as indicated by the arrows in Fig. 2, strikes the flange portion 24 of the tube 23 forcing the latter forwardly within the bore to the position as shown in Fig. 2 with its outer end adjacent the upper end of the nozzle 16, it being observed that the axis of the tube 23 and bore 21 intersect the axis of the nozzle 16 adjacent the upper end of the latter. As the operator continues to manipulate the bulb 27, the air flowing out of the tube 23 passes over and about the upper end of the nozzle 16, thus promoting a partial vacuum at the top of the tube and, as is well known, this causes the liquid within the container 10 to rise within the tube 17 and the nozzle 16, the liquid emerging from the top of the nozzle being sprayed or atomized by the air flowing thereby. Each time the bulb 27 is allowed to expand, the tube 23 will return to its initial position as shown in Fig. 1, the tube being moved outwardly as indicated in Fig. 2 each time the bulb is compressed. Hence, any droplets of solution which may be clinging to the upper end of the nozzle 16 will not dry in contact with the end of the tube 23, nor will a portion of the mist or spray be drawn into the bulb 27, as is the case in conventional atomizers where the tube corresponding to the nozzle member 16 is affixed adjacent the orifice through which the air is forced. As a result the atomizer of this invention may be used repeatedly without the latter becoming clogged during the intervals of non-use even though quick drying and/or relatively adhesive solutions are employed.

As mentioned previously, the internal diameter of the tube 17 is several times the diameter of the bore in the nozzle member 16 and the length of the tube 17 is several times that of the nozzle member. Hence, when use of the atomizer is terminated, the liquid which has been drawn upwardly within the tube 17 and the nozzle member 16 will readily drop to the common level of the

liquid in the container 10. This follows from the fact that the internal diameter of the tube 17 is sufficiently large so that there is no appreciable capillary effect therein so that the liquid therein falls by gravity as soon as flow of air past the top of the nozzle is terminated. Since the column of liquid in the tube 17 is relatively large with respect to that in the nozzle member 16, the vacuum produced by the descent of the former will draw the liquid out of the bore in the nozzle member, thus overcoming the tendency of the liquid to remain in the latter due to capillary action and the adhesiveness of the liquid. Therefore, the bore of the nozzle member 16 is automatically substantially freed of the liquid immediately after use of the atomizer is terminated.

If cleaning of the atomizer becomes necessary, this operation can be more readily effected than in prior art devices by virtue of the novel construction of the atomizer of this invention. This follows from the fact that the nozzle 16 and the tube 23 are normally spaced from each other and extend at an angle with respect to each other so that the end of each is accessible for cleaning without undue interference. Hence it is only necessary to withdraw the rod 19 from its opening within the cap 12 and insert the latter within the nozzle member 16 to clear any obstructions therefrom. Likewise, the rod 19 may be readily inserted into the tube 23, after removing any solution clinging to the rod, without the necessity of taking the atomizer apart. However, this latter operation should not ordinarily be necessary since the solution will not enter the tube 23 during normal use due to the automatic retraction of the tube. If it be desired to thoroughly cleanse the device, as, for example, when it is to be used with an entirely different kind of solution, the parts may be readily disconnected for separate cleaning.

While the present preferred embodiment of an atomizer constructed in accordance with the invention has been illustrated and described in considerable detail, it will be apparent that numerous modifications and adaptations may be made by those skilled in the art without departing from the spirit of the invention. Thus, the angle between the tube 23 and the nozzle 16 may be varied and changes may be made in the positions and configurations of various other parts of the device. Moreover, a bayonet or other type of connection may be employed instead of screw threads to attach the cap member 12 to the container 10. Also, the cap member may be made to fit the necks of bottles or containers in which the lacquer or other solution is sold so that a separate flask or container 10 is not necessary. Also, the bushing or sleeve 25 may be omitted and the movable tube 23 prevented from being drawn into the bulb 27 by means of an external flange on the tube adjacent its outer end.

Other modifications will readily occur to those skilled in the art and, therefore, the invention is not to be considered as limited to the exact details of construction or arrangements of parts illustrated and described but only by the spirit and scope of the appended claims.

Having thus described the invention, I claim:

1. An atomizer comprising a cap member adapted to be attached in an opening of a container for a liquid to be sprayed, said cap member having an opening extending therethrough, a tube having its upper end positioned in the opening in the cap and its lower end extending adjacent the bottom of the container, a nozzle member extending above said cap and having a

bore therethrough communicating with said tube, a resilient syringe bulb having an air exhaust opening, a longitudinally movable tube forming a part of the path for the air issuing from the exhaust opening of said bulb, means carried by said cap for supporting the said bulb and movable tube with the outer end of the latter spaced from the upper end of said nozzle member and with the axis of said movable tube intersecting the axis of said nozzle adjacent the upper end of the latter, and a flange on said movable tube adjacent its inner end adapted to be engaged and moved by the air exhausted from said bulb thereby moving the outer end of said movable tube adjacent the upper end of said nozzle member so that liquid is drawn upwardly from the container through the nozzle member and is divided into a fine spray by the air issuing from said movable tube.

2. An atomizer comprising a cap member adapted to be attached to an opening in a container for the liquid to be sprayed, a tubular member extending through an opening in said cap member in sealing relationship, with the lower end of said tubular member extending into the liquid in the container when the cap member is positioned thereon, means for producing a flow of air past the upper end of said tubular member including a longitudinally movable tube forming a part of the path for the air, means carried by said cap for supporting said air flow producing means with the axis of said movable tube intersecting the axis of said tubular member adjacent the upper end of the latter and with the outer end of said movable tube spaced from the upper end of the tubular member, and means on said movable tube adjacent its inner end adapted to be engaged and moved by the air flowing from said air producing means thereby moving the outer end of said movable tube adjacent the upper end of said tubular member so that liquid is drawn upwardly from the container through the tubular member and is divided into a fine spray by the air issuing from the movable tube.

3. An atomizer of the type defined in claim 2 and in which the axis of said movable tube is inclined with its inner end at a lower elevation than its outer end so that the said movable tube moves away from said tubular member when the air is not flowing from said producing means.

4. An atomizer comprising a cap member adapted to be attached to an opening in a container for the liquid to be sprayed, a tubular member extending through an opening in said cap member in sealing relationship, with the lower end of said tubular member extending into the liquid in the container when the cap member is positioned thereon, a resilient syringe bulb having an air exhaust opening, a longitudinally movable tube forming a part of the path for the air issuing from the exhaust opening of said syringe bulb, means carried by said cap for supporting said bulb and the said movable tube with the outer end of the latter spaced from the upper end of the tubular member and with the axis of said movable tube intersecting the axis of said tubular member adjacent the upper end of the latter, and means on said movable tube adjacent its inner end adapted to be engaged and moved by the air exhausted from said bulb thereby moving the outer end of said movable tube adjacent the upper end of said tubular member so that liquid is drawn upwardly from the container through the tubular member and is divided into a fine spray by the air issuing from the movable tube.

5. An atomizer comprising a cap member adapted to be attached to an opening in a container for the liquid to be sprayed, said cap member having an opening therethrough adapted to communicate with the interior of the container to which it is attached, a plug member removably fitted in the opening of the cap member and having an opening extending therethrough, a tube having its upper end positioned in the lower end of the opening in the plug member and its lower end adapted to extend into the liquid in the container when the cap member is attached thereto, a nozzle member fitted in the upper end of the opening in said plug member and having a bore therethrough communicating with said tube, a resilient syringe bulb having an air exhaust opening, a longitudinally movable tube forming a part of the path for the air issuing from the exhaust opening of said bulb, means carried by said cap member for supporting said bulb and said movable tube with the outer end of said movable tube spaced from the upper end of said nozzle member and with the axis of the movable tube intersecting the axis of said nozzle member adjacent the upper end of the latter, and means on said movable tube adjacent its inner end adapted to be engaged and moved by the air exhausted from said bulb thereby moving the outer end of said movable tube adjacent the upper end of said nozzle member so that liquid is drawn upwardly from the container through the nozzle member and is divided into a fine spray by the air issuing from the bulb.

6. A liquid atomizer comprising, a liquid supply member having a discharge orifice; an air discharge member having an orifice for directing a stream of air transversely of the axis of the first mentioned orifice, said air discharge member being movable between two positions by the passage of air directed therethrough for moving the discharge orifice thereof from a position relatively remote from the discharge orifice of the liquid supply member to a position adjacent the discharge orifice of the liquid supply member; and means for directing air under pressure through the air discharge member.
